UNITED STATES PATENT OFFICE.

LOUIS IWAN, OF STREATOR, ILLINOIS.

DITCHING-SPADE.

SPECIFICATION forming part of Letters Patent No. 573,597, dated December 22, 1896.

Application filed June 8, 1895. Serial No. 552,105. (No model.)

To all whom it may concern:

Be it known that I, LOUIS IWAN, a citizen of the United States, residing at Streator, in the county of La Salle and State of Illinois, 5 have invented a new and useful Improvement in Ditching-Spades, of which the following is a specification.

My invention relates to an improvement in the class of ditching-spades in which the 10 blade of the implement is of skeleton shape, to present the least possible surface area for the adhesion of the soil dug by it and to render the blade open for readily draining off through it the water taken up in the soil.

15 The primary object of my invention is to improve the blade of a ditching-spa de of the variety referred to in matters of detail, whereby the blade shall be provided with an especially desirable construction of extended foot- 20 step, formed as an integral part of the blade, to afford a better purchase to the foot of the user in digging, the construction avoiding front and back flanges on the upper edge of the blade, which, when provided, afford at- 25 taching-surfaces for clay and mucky soil; whereby the point of the blade shall be strengthened, and whereby the back of the blade shall be adapted to facilitate its penetration into the soil being dug.

30 Referring to the accompanying drawings, Figure 1 shows my improved ditching-spa de by a view in front elevation. Fig. 2 is a section taken at the line 2 on Fig. 1, viewed in the direction of the arrow and enlarged; Fig. 35 3, a section taken at the line 3 on Fig. 1, viewed in the direction of the arrow and enlarged; and Fig. 4, a view showing the blade in rear elevation.

A is the blade, formed in one piece, of steel, 40 of the general concavo-convex form in cross-section represented by Figs. 2 and 3. At opposite sides of the longitudinal center of the blade the metal is omitted, affording elongated openings r and r', having the straight 45 sides illustrated, the straight upper ends with slightly-rounded corners, and the roundly-converging edges at the lower ends, whereby the junction of the bars p, p', and p², formed by the openings r and r', with the point or cutting end o of the blade is expanded, as shown at n, n', and n², there to strengthen the blade thus at points where it is subjected to the greatest strain in the prizing operation in digging. The upper end of the blade is in

the form of a concavo-convex cross-bar m, 55 flat on its upper side and beveled on its rear side, as shown at t, in a downward and forward direction to form a narrow edge along its under side, the better to penetrate and shed the soil, and the front and rear sides of 60 the bar m are flush with the adjacent surfaces of the blade. The opposite ends of the bar m, to which the handle B is attached, (as by engagement with a socket q, extending outward from the center of the bar,) are ex- 65 tended outward beyond the side bars p' and p² to afford foot-steps m' and m², beveled on their rear sides, as shown at v, from the outer ends to their junction with the side bars, which latter, as also the central bar p, are 70 substantially V-shaped in cross-section, with the apices extending along their backs, the better to adapt the bars for cutting, and the beveled sides v of the foot-steps form, practi- 75 cally, outwardly-curved continuations of the outer beveled sides of the bars p' and p².

By my improved construction thus described the spade is rendered peculiarly strong and easy of action in digging the soil and cleaning itself in throwing off the soil it 80 has dug, and the extensions of the top bar, affording the foot-steps, which latter are useful also on the blades of other varieties of spades and shovels, facilitate digging by presenting expanded flat purchase-surfaces, each 85 for a foot of the operator.

What I claim as new, and desire to secure by Letters Patent, is—

In a ditching-spa de, the blade A, concavo-convex in cross-section and formed with the 90 cutting end o, openings r and r', and longitudinal bars p, p' and p² at the sides of said openings, said bars having the expanded junctions n, n' and n², with said cutting end and being substantially V-shaped in cross-section 95 with the apices extending along their backs, and the bar m at the upper end of said longitudinal bars, beveled on its rear side and flush with the front and rear surfaces of the blade and provided with end extensions hav- 100 ing the beveled surfaces v and forming foot-steps m' and m², as and for the purpose set forth.

LOUIS IWAN.

In presence of—

GEORGE W. ROSE,
THEO. ROCKENFELLER.
